By his Attorney *S. Chas. Yeaton.*

UNITED STATES PATENT OFFICE.

DAVID J. WICKERS, OF NEW YORK, N. Y.

GARMENT-FASTENER.

No. 903,930

Specification of Letters Patent.

Patented Nov. 17, 1908.

Application filed June 6, 1907. Serial No. 377,620.

To all whom it may concern:

Be it known that I, DAVID J. WICKERS, a citizen of the United States, and a resident of the borough of Brooklyn, county of Kings, city and State of New York, have invented certain new and useful Improvements in Garment-Fasteners, of which the following is a full, clear, and exact specification.

My invention relates to garment fasteners and comprises the hereinafter more particularly described device, whereby wearing apparel such as is commonly worn by women and children, may be more satisfactorily fastened together than heretofore by the fastening devices that are commonly used.

My improved fastener may be used wherever the ordinary hook and eye is applicable, but is constructed and is devised to overcome the defects of such fastener.

My invention, as shown in the accompanying drawings forming part of this specification, comprises a stud member and a metal wire spring attached respectively on opposite edges of the garment. The spring member is adapted to be sprung over and snugly fit upon the stud and the parts are so constructed as to insure a ready and secure engagement.

Referring to the drawings: Figure 1 is a plan view of the stud member. Fig. 2 is a vertical central section of Fig. 1. Fig. 3 is a plan view of the spring member. Fig. 4 is a vertical central section showing the two members in engagement. Fig. 5 is a plan view of the device showing the method of securing it to fabric. Figs. 6 and 7 are perspective views showing a ready way of unfastening the device. Figs. 8 and 9 are plan views showing modifications of the spring member. Figs. 10, 11 and 12 are plan views of the stud member showing respectively four holes, a transverse rib and cross-ribs for sewing the stud to the garment. Fig. 13 is an enlarged sectional view of the stud member and Fig. 14 is an enlarged sectional view showing the two members in engagement.

The stud is preferably stamped from non-rustable sheet metal and comprises a circular central top portion *a*, slightly hollowed or bowl-shaped, and punched with perforations *b* for sewing the stud to the garment. The blank is bent or turned downward along the periphery of the top *a* forming the side wall *c*, and outward again forming the shoulder *e* and circular flange *d*. The wall *c* should slightly flare outward at the top.

The spring member is preferably made from non-rustable wire having a sufficient amount of resiliency for the purposes intended. It comprises an annular spring *f*, open at the rear forming a throat *g* and is connected to and made integral with the loops *h*, adapted for sewing the spring to the garment.

The stud of my fastener is usually sewed to the under-lap of the garment as shown in Figs. 5, 6 and 7, in the usual way in which buttons and the like are ordinarily secured. For that purpose the bowl-shaped top *a* may be provided as shown in Figs. 1, 10, 11 and 12 with either two or four holes or the blank may be stamped out, leaving a central rib. In most instances the two holes for sewing-thread will suffice. The depression in the top *a* is well adapted for containing the sewing-thread and gives a neat finish to the fastener.

The spring member is sewed to the overlap of the garment as shown in Figs. 5, 6 and 7, the lap being broken away to facilitate a better showing of the device. The spring is sewed in the usual way in which an eye of the ordinary hook and eye is secured, and in fact such an eye may be utilized, but it is much preferable for the proper working of my device that the principle involved in the construction shown in Figs. 3, 8 and 9 be utilized. In the eye of the ordinary hook and eye the wires at the throat *g* are carried back and the ends forming the loops for the sewing-threads are then turned around on the outside of the loop in a reverse order from that shown in Figs. 3, 8 and 9, that is, the eye is given a long throat and is secured by sewing the throat to the garment. Such a construction is not feasible for my device, as the sewing together of the wires forming the throat prevents the utilization of the member as a spring. I therefore turn the loops *h*—*h* in a reverse order to the ordinary eye bringing the ends of the wire on the inside, enabling the spring to be sewed apparently as it is usually done in the ordinary eye, but in reality leaving the member free to be used most effectively as a spring.

Fig. 8 differs from Fig. 3 only, in providing the side loops *h* to enable the over-lap to be secured much nearer to the edge of the goods which prevents the very undesirable flapping or turning backwards of the lap which is generally apparent where the ordinary hook and eye is used. It also prevents

the receding of the goods which leaves an open gap caused by undue stretching of a tight-fitting garment, exposing to view the fastening device. This form is especially useful on a tight fitting garment as on the placket of women's skirts and the back of shirt-waists.

Where the hook and eye is used it is necessary to make the over-lap sufficiently wide to conceal both the hook and the eye which manifestly increases its tendency to flap back and the closure to stretch open, whereas the stud of my fastener fits entirely within the spring member, making it necessary to have the over-lap of a width only sufficient to conceal the spring member.

The stud is the same height as the spring member and makes a flush connection therewith on the top (see Fig. 4.) The sewing-threads lie in the bowl-shaped cavity below the upper surface, and the whole making a very flat fastener, which is especially desirable on outside garments. The parts are well adapted to receive such pressure as is employed in ironing wearing apparel and are not subjected to the danger of the ordinary hook of being jammed together by the weight of the flat iron and rendered useless; moreover hooks are apt to accidentally hook into lace or the like and tear it.

To secure my fastener together the spring has only to be brought over the stud and when registering therewith can be snapped down into its seat on the flange *d* by a slight pressure of the finger. The diameter of the wall *c* is made slightly larger than the inner diameter of the spring *f*, so that the pressure exerted to engage the two parts spreads the spring at the throat *g*, allowing it to snap into and remain in spring-pressed engagement with the stud. The flaring of the wall *c* aids in retaining it in this engagement.

To disengage the fastener the tip of the thumb is brought beneath the over-lap and

placed upon the top of the stud; at the same time the other hand tilts the spring member by raising its rear end as shown in Figs 6 and 7. The spring is in this way gradually forced over the flare of the wall *c* (instead of all at once), making an easy disengagement of the members.

Fig. 9 shows the spring more spread at the throat and is desirable for large fasteners, the increased width enabling the members to be more easily disengaged.

I claim as my invention:—

1. A fastener comprising a stud and a spring member, the spring member comprising an annular spring open at the rear, and a pair of loops for sewing thread, the loops being integral with the spring at the opening and in the same plane therewith, said stud being adapted to fit within the spring of the spring member and being composed of a circular base flange to seat on the garment material, an annular side wall flaring outwardly at the top and a top wall, having thread openings therein, said spring member being of the same height as said top wall.

2. A fastener comprising a stud and a spring member, the spring member comprising an annular spring open at the rear, and a pair of loops for sewing thread, the loops being integral with the spring at the opening and in the same plane therewith, said stud being adapted to fit within the spring of the spring member and being composed of a circular base flange to set on the garment or other material, an annular side wall flaring outwardly at the top, and a top wall, formed bowl shaped to provide a thread receiving depression and being formed with thread openings therein, said spring member being of the same height as said top wall.

DAVID J. WICKERS.
